GOVERNOR SLEEVE DISLODGING AND
REMOVING TOOL

William G. Smith, Laramie, Wyo.

Application February 21, 1944, Serial No. 523,308

2 Claims. (Cl. 29—261)

This invention relates to a novel tool or implement which is especially adapted for several types of machines using sleeve governors, the same being particularly useful in dislodging and then removing the sleeve, but being adaptable to accommodate other types and kinds of bushings and sleeve-like elements.

It has been the practice in the past to remove shafts from dynamos and water pumps and then put the same in a vise and pound the sleeve off with a hammer and a chisel, or any other device or tool at hand. This takes considerable time, obviously. And, too, governor sleeves stick and are extremely difficult to remove. The purpose of the present invention is to provide a novel structural tool or implement which is especially applicable to remove sleeve governors, and it is my aim, in carrying out the principles of the invention, to provide a structure which is comparatively simple, economical, easy to handle, and which is reliable in achieving the desired aim.

The preferred embodiment of the invention is characterized by a sturdy frame structure in the form of an adapter yoke, there being slidably and adjustably mounted thereon a double jaw unit so constructed and coordinated with the other parts as to provide an over-all structural adaptation which lends itself admirably well to accomplishing the results desired.

Other structural features and advantages of the invention will become more readily apparent from the following description and the accompanying illustrative drawings.

In the drawings, wherein like numerals are employed to designate like parts throughout the same:

Figure 1 is an elevational view of a sleeve dislodging and removing tool or device constructed in accordance with the principles of the present inventive conception.

Figure 2 is a top plan view of the structural arrangement seen in Figure 1.

Figure 3 is an end elevation of the structure appearing in Figures 1 and 2.

Figure 4 is a fragmentary detail elevational view through the central or hub portion of the structural assemblage as a whole.

Figure 5 is a top plan view of the arrangement of parts depicted in Figure 4.

Figure 6 is a section on the line 6—6 of Figure 1 looking downwardly in the direction of the arrows.

Referring now to the drawings by distinguishing reference numerals, it will be observed that the preferred embodiment of the invention is

characterized by two major units or parts; namely, the foundation or frame structure A and the dual adjustable, slidable sleeve-gripping unit B.

The frame is made up of a pair of spaced, parallel, longitudinal frame bars 7. I provide three assembling and spacing blocks; two outer duplicate blocks 8 and 9 secured between the frame bars by rivets 10. These blocks 8 and 9 have their outer ends spaced inwardly from the corresponding outer ends of the frame bars and their inner ends spaced from the central adapter block 11 also held in place by rivets 12. This central block 11 is provided with a seating notch 13 and the frame bars on opposite sides thereof are provided with aligned supplemental notches 13a. The limbs or arms of the frame unit are denoted by the numeral 14. These are disposed at the opposite ends of the frame structure and have their upper or inner ends bolted, as at 14a, between the frame bars and against the adjacent ends of the spacing blocks 8 and 9. The spacing blocks are provided with integral upstanding lugs 15 having screw threaded holes, said lugs functioning as nuts for the threaded ends 16 of the bolts 17. The outer ends of the bolts are provided with wing nuts 18 and the adjacent end portions are rotatable in the companion lugs 19 formed integral on the upper ends of the limbs 14. The lower free ends of the limbs are provided with detents or retaining pins 20. So much for the frame and other parts associated directly therewith.

Coming now to the specific construction of the jaw unit B, it will be observed that this comprises a pair of elongated jaw members 21 disposed in parallelism and having their lower ends suitably tapered and shaped to provide gripping elements 22 for the sleeve 23 (see Fig. 6) in an obvious manner. These jaw members 21 pass upwardly through the guide openings formed between the central block 11 and the adjacent inner ends of the complimentary spacing blocks 8 and 9. The protruding upper ends are provided with bolt holes 24 to selectively accommodate bolts 25 passing through the furcations or ears 26 provided at the outer ends of the crosshead 27. The central body portion 28 is screw threaded to accommodate the set screw 29. The adjusting and retaining bolts 17 atop the frame structure have their inner ends engageable with the adjacent intermediate portions of the jaw members 21. The set screw has its lower end pointed and engageable in the seats or notches 13 and 13a. Thus, the bolts 25 can be loosened and tightened to make for adjustment of the jaw-equipped members 21 by way of the bolts 17. Then, the set

screw 29 can be used to bodily shift the entire unit B at right angles to the frame structure A in an obvious manner to dislodge and remove the sleeve, collar or part 23 from its shaft (not shown).

The aligning and adjusting wing-head bolts 17 are loosely turnable in the guide and assembling lugs 19 and the inner threaded ends are fed through the nut-like lugs 15 to engage the parts 21, sometimes referred to as straddle bars. Incidentally, these straddle bars are reversible. That is to say, they can be removed from the retaining ears 26 by detaching the bolts 25. This permits the jaw ends or elements 22 to be turned outwardly instead of inwardly toward each other, as shown in Figure 1 of the drawings.

Although the invention is shown and described as especially adaptable for removing collars and sleeves such as are used in different types of machines employing sleeve governors, it is evident that the construction is such as to permit the parts to be rearranged and adapted for handling bushings, thimbles and the like in other types of machinery.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and arrangements of parts may be resorted to in actual practice so long as no departure is made from the invention as claimed.

I claim:

1. In a governor sleeve dislodging and removing tool, a frame structure comprising a pair of longitudinally extending, parallel frame bars, an intermediate block fastened between the intermediate portions of said frame bars, a pair of end blocks fastened between the end portions of

said frame bars and having their inner ends spaced from the intermediate block to provide guide openings, and having their outer ends spaced inwardly from the outer ends of the frame bars, and a pair of limbs having their upper ends bolted between the outer ends of the frame bars and abutting the outer end portions of the outer spacing blocks, the lower ends of said limbs being reduced to provide detents, inner and outer lugs rising in spaced pairs from the top portion of said frame structure, the respective inner lugs being provided with screw-threaded bolt holes and the outer lugs having openings to accommodate and provide bearings for bolts, and bolts passing through the bearings in said outer lugs and having their inner ends screw-threaded and threaded into the bolt holes in said inner lugs.

2. In a governor sleeve dislodging and removing tool, a frame structure comprising a pair of longitudinally extending, parallel frame bars, an intermediate block fastened between the intermediate portions of said frame bars, a pair of end blocks fastened between the end portions of said frame bars and having their inner ends spaced from the intermediate block to provide guide openings, and having their outer ends spaced inwardly from the outer ends of the frame bars, and a pair of limbs having their upper ends bolted between the outer ends of the frame bars and abutting the outer end portions of the outer spacing blocks, the lower ends of said limbs being reduced to provide detents, and a bodily adjustable double-jaw unit including a crosshead having a central screw threaded body portion and bifurcated ends, the furcations constituting assembling ears, a set-screw passing through the screw threaded body portion, a pair of jaw-equipped members, the upper ends thereof being bolted detachably between said ears and the jaw-equipped ends being slidable through said guide openings.

WILLIAM G. SMITH.
